RANGE FINDER

Frederick M. E. Holmes and Joseph Mihalyi,
Rochester, N. Y., assignors to Eastman Kodak
Company, Rochester, N. Y., a corporation of
New Jersey

Application March 13, 1943, Serial No. 479,098

8 Claims. (Cl. 88—2.7)

1

This invention relates to range finders.
This is Case H of a series of applications relating to this same subject. The series includes the following:

Title	Serial No.	Filed	Inventors
Mount for optical elements.	461,584	Oct. 10, 1942	Mihalyi.
Range finder construction.	461,585	Oct. 10, 1942	Do.
Range finders—Case A.	472,831	Jan. 19, 1943	Do.
Range finders—Case B.	472,832	Jan. 19, 1943	Do.
Range finders—Case C.	472,833	Jan. 19, 1943	Do.
Range finders—Case D.	472,834	Jan. 19, 1943	Do.
Range finders—Case E.	472,835	Jan. 19, 1943	Mihalyi, MacNeill.
Range finders—Case F.	479,096	Mar. 13, 1943	Mihalyi, Tuttle.
Range finders—Case G.	479,097	Mar. 13, 1943	Mihalyi.
Range finders—Case I.	479,099	Mar. 13, 1943	Do.
Range finders—Case J.	479,100	Mar. 13, 1943	Mihalyi, MacNeill.
Range finders—Case K.	479,101	Mar. 13, 1943	MacNeill, Holmes.
Range finders—Case L.	479,102	Mar. 13, 1943	Mihalyi, MacNeill.
Range finders—Case M.	491,954	June 23, 1943	Mihalyi.
Range finders—Case N.	491,955	June 23, 1943	MacNeill.
Range finders—Case O.	491,956	June 23, 1943	MacNeill.
Range finders—Case P.	505,016	Oct. 5, 1943	MacNeill, Mihalyi.
Range finders—Case T.	508,186	Oct. 29, 1943	MacNeill.

The present Case H relates to an invention which constitutes an improved embodiment or, from one point of view, a species of Case A of this series and includes many additional and important features. The object of the invention is to provide a simplification of the operation of this type of range finder, to provide symmetry and accuracy of construction and to provide increased ease and speed of operation thereof.

Cases A, B and C describe autocollimating range finders in which an image of one adjustment coincident element is projected adjacent to the other, the element light beam passing through the range finder optical system to compensate for any maladjustment therein. The range indicating elements may be a scale and index or a coincidence line and fiducial mark, as particularly described in Case E and/or as used as an indication of maladjustment as described in Case F. The prime feature of the present Case H resides in the fact that element beams are projected from both elements, forming images thereof adjacent to one another in a single plane. The elements themselves may be in separate planes or in the same plane, but in every case the images of the two elements are in a single plane wherein they are viewed by the main observer or by an auxiliary observer.

Thus, in a range finder having an autocollimating arrangement involving an element light beam traversing the optical system of the range finder,

the present invention is characterized by having this element light beam made up of two parts, one from each of the two elements respectively and forming in a single plane, images of the elements adjacent to one another. These images are moved relative to one another, by anything which similarly affects the object images, i. e. by any maladjustment of either half of the range finder system or by the ranging adjuster itself. 10 Of course, this may be accomplished directly by having the ranging adjuster operate on the element light beam. In one embodiment of the invention the elements are at least optically in the comparison planes of the range finder, which may be coplanar as in a coincidence type range finder, and light beams from these two elements are projected into focus in a third plane. This first embodiment is also particularly useful in stereo range finders, wherein the comparison planes are 15 in general separate. In a second embodiment, the elements are in independent planes, separate or coplanar and images thereof are formed by element light beams passing through the range finder optical system to the eyepiece to be viewed by the main observer while ranging.

A third embodiment which is a species of the second one applied to coincidence type range finders has the adjustment coincident elements in separate planes to one side of the range finder system and rigidly or at least accurately fixed to lenses so that each element is associated with, and is in the nodal plane of, one lens and at the same time is in the focal plane of the other lens. Thus each lens serves to collimate the light from the other element and these collimated beams are, by small optical squares near each viewing point of the range finder, reflected into the two halves of the range finder system and thence through the objective or objectives of the range 30 finder into focus in the comparison plane. The use of this mutual nodal focal plane arrangement eliminates the errors due to relative movement of the elements as is known in other systems which do not relate to the present invention. The elements may be simply a scale and index to be read by the main observer or may be a coincidence line and fiducial mark, whose images are to be brought into coincidence by the main observer who simultaneously operates some form of scale and index to be read by an auxiliary observer or to be fed mechanically into a military fire director. Other objects and advantages of the invention will be understood from the following description when read in connection with the accompanying drawings in which:

Fig. 1 is a perspective view of an optical system incorporating one embodiment of the invention, Fig. 2 is a plan view of the arrangement shown in Fig. 1.

Fig. 16 illustrates an embodiment slightly different from that shown in Fig. 15.

Fig. 17 shows an embodiment of the invention which differs from Fig. 13 by the use of coincidence lines.

Fig. 18 is an enlarged view of one detail of Fig. 17.

Fig. 19 is a plan view of a range finder incorporating the optical system shown in Fig. 17.

In Figs. 1, 2 and 3, light from an object being ranged is reflected by penta prisms 21 to crossed reflectors 22 and 23 and thence through an objective 24 forming images in a comparison plane 25 to be viewed by the eye 26 of an observer, who adjusts the images by means of a light deviator 30 until they are in coincidence. According to the invention there are engraved on the comparison plane, an index 34 and a scale 37 which are respectively illuminated by lamp 32 and prism 33 and lamp 35 and prism 36. Light from these adjustment coincident elements 34 and 37 is collimated by the objective 24 and is reflected respectively by prisms 22 and 23 to the penta prisms 21. These element light beams are then picked up by small penta prisms 38 and 39 and directed toward a prism 40 whose surfaces are silvered to reflect both beams upward through a lens 41 and into focus on an image plane 42, forming images 34' and 37' which may be viewed by the eye 43 of an observer.

The main observer whose eye is shown in Fig. 1, adjusts the light deviator 30 until the object images are in coincidence at which time the observer whose eye is shown at 43 reads the range as indicated by the element images 34' and 37'.

Figs. 4 and 5 illustrate a stereo range finder in which light from the object being ranged is received by penta prisms 50 and is focused by objectives 51 in comparison planes 52 which carry stereo reticle marks 53. The images and the reticle marks are viewed stereoscopically through prisms 54 and eyepieces 55 by the right and left

eyes 56 of an observer. A light deviator 57 is adjusted until the apparent object distance is the same as the apparent mark distance. According to the invention, one of the image planes is provided with an index 62 illuminated by a lamp 60 and prism 61 and the other image plane is provided with a scale 66 illuminated by a lamp 64 and a prism 65. Light from these two adjustment coincident elements 61 and 66 is collimated by the objectives 51 and directed by the penta prisms 52 into small auxiliary penta prisms 63 and 67 respectively which in turn direct the beams toward reflectors 68 and upward through an objective 69 into focus forming images 62' and 66' in a range indicating plane 70 to be viewed by the eye 71 of an observer.

In Fig. 6 there is shown a slight variation of the arrangement shown in Fig. 1 since the adjustment coincident elements are not located in the comparison planes, but in the optical equivalent thereof. In Fig. 6 light from the object being ranged is directed by penta prism 75 to crossed reflectors 76 and is focused by an objective 77 in coplanar comparison planes to be viewed through an eyepiece 78 by the eye 79 of an observer. Coincidence is obtained by adjusting a light deviator 80. Since anything which affects one of the object beams between its reflector 76 and the eye 79, similarly affects the other object beam, the element light beams need only traverse those parts of the range finder system which are optically ahead of the reflectors 76, including the reflectors 76 themselves. Light from a lamp 81 illuminates adjustment coincident elements on a transparent element 82 and this light is collimated by a lens 83 so that the element beams are reflected respectively by the backs of the reflectors 76 toward the penta prisms 75. These element beams are then reflected by auxiliary penta prisms 84 toward reflectors 85 and upward through a lens 86 to an image plane 87 to be viewed by the eye 88 of an auxiliary observer. The elements 85, 86, 87 and 88 correspond exactly to elements 40, 41, 42 and 43 of Figs. 1 to 3.

Fig. 7 is similar to Fig. 6 but differs in a few details. Light from the object being ranged is reflected by prisms 90 through objective 91 toward crossed reflectors 92 and into focus on an image plane 93 which is viewed through an eyepiece 94 by the eye 95 of an observer. Coincidence is obtained by adjusting a light deviator 96. Light from a lamp 97 illuminates a scale and index engraved on transparent element 98 which is located on the opposite side of the reflectors 92 from the image plane 93, and at the same distance therefrom. Thus, light from the adjustment coincident elements is collimated by the objectives 91 and is directed by small penta prisms 99 and 100 which are facing in the same instead of opposite directions, through an objective 101 which brings them to focus in an image plane 102 forming images 104 and 105 as best seen in Fig. 7A, to be viewed by the eye 103 of an observer. The advantages of this system over that shown in Figs. 1 and 6, lie in the elimination of the reflectors 40 and 85 respectively.

Fig. 8 is similar to Fig. 1, but employs in place of the scale 37 and index 34, a coincidence line and fiducial mark. Light from the lamp 35 passes upward through a disk 110 on which is engraved a coincidence line in the form of a spiral 111. Actually this spiral is positioned in the focal plane of the objective 24, by having the disk up close to the element 25 and the prism 36 behind the element 25, but it is shown sepa-

rated therefrom in Fig. 8 for clarity. Fiducial marks 113 are also engraved on the element 25. Light from these two adjustment coincident elements, the coincidence line and fiducial marks, is brought to focus forming images 111' and 113' in the image plane 42. When coincidence of the object images in the image plane 25 is obtained by adjusting the light deviator 30, the observer whose eye is shown at 43 rotates the disk 110 until the image 111' of the coincidence line falls exactly between the fiducial spots 113'. For convenience, a scale 112 is engraved adjacent to the coincidence spiral 111. The image 112' of this scale employs the fiducial marks 113' as an index and the range may be read directly by the observer whose eye is shown at 43.

A somewhat similar arrangement is shown in Fig. 9 in which a rotatable disk 117 carries a circle 118 which acts as a fiducial mark and a spiral 119 which constitutes the coincidence line. These elements are illuminated by lamps 115 and prisms 116. When the observer whose eye is shown at 26 obtains coincidence of the object images by operation of the light deviator 30, the observer whose eye is shown at 43 rotates the disk 117 until the images 118' and 119', corresponding to the fiducial mark 118 and coincidence line 119, are in register. At this time an observer whose eye is shown at 122 reads the range from a scale 120 engraved on the disk 117 and an index 121. The eyes 26 and 122 may be the right and left eyes of the same observer and the observer whose eye is shown at 43 may operate the disk 117 continually, while ranging, to maintain register of the images 118' and 119'. In this way, the main observer may read the range as soon as he obtains coincidence.

Figs. 10 to 19 illustrate embodiments of the invention employing a preferred feature which by itself is not novel with this particular disclosure, but which is useful when projecting to a single plane, images of two cooperating adjustment coincident elements. In Figs. 10, 11 and 12, light from the object being ranged is received by penta prisms 125 and is reflected by crossed reflectors 126 through an objective 127 into focus in an image plane 128 to be viewed through an eyepiece 129 by the eye 130 of an observer. These object beams form images 131 as best seen in Fig. 12. Coincidence is obtained by adjusting a light deviator 141. According to the invention, light from lamps 135 as reflected by prisms 136 passes adjustment coincident elements, which themselves are not shown but whose images appear as 139 and 140 in Fig. 12. These adjustment coincident elements are engraved on lenses 137 or attached thereto so as to be substantially at the nodal planes of each lens. These lenses are of equal focal length and are separated by a distance equal to the focal length so that the light from each adjustment coincident element is collimated by the other lens. The resulting element beams are picked up by small penta prisms 138 and directed into the range finder optical system, automatically to form images 139 and 140 in the comparison planes 128. The purpose of this nodal-plane-focal-plane system is to prevent maladjustment of this auxiliary system having any effect on the reading. If one of the lenses together with its adjustment coincident element is moved slightly sideways so that its image appearing in the comparison plane 128 moves slightly sideways, this same movement shifts the element beam coming from the other adjustment coincident element by an equivalent

amount so that its image moves equally and reading of the scale 140 and index 139 remains unchanged, although both images are moved to one side slightly.

Figs. 13 to 16 are similar to Fig. 10 but two objectives 145 are used in place of the single objective 127 and the comparison planes are in a somewhat more complicated prism assembly consisting of cross prism 146 and 147 on the latter of which is cemented a rhomb 148 to receive the incoming beam at the same level as the beam reaching the prism 146. Light from these crossed prisms 146 is reflected to 30° right angle prisms 149 and 150 whose interface 151 consists of two portions one of which, 153, is clear and the other of which, 152, is reflecting. As shown by the ray 161 in Fig. 15 light from the prism 146 is reflected down to the reflecting surface 152 and thence upward to the eye 163 of an observer. As shown by the ray 162 on the other hand, light from the prism 147 is reflected up by the prism 150 and through the transparent area 153 to the eye 163. This arrangement permits the observer whose eye is shown at 163 to see both the object images which are to be adjusted for coincidence and the scale and index.

An alternative arrangement shown in Fig. 16 has the scale and index so positioned that the element beams do not reach the eye 163. The light from the scale as shown by the ray 165 passes downward through the transparent area 153 to the eye 167 of an auxiliary observer and similarly as shown by the ray 166 light from the index is reflected from the bottom of the reflecting surface 152 downward to this eye 167.

Figs. 17 to 19 show a similar arrangement in which a fiducial mark and coincidence line replace the scale and index of Fig. 13. The fiducial mark is practically identical to the index mark used in Fig. 13. The coincidence line is in the form of a spiral 171 carried on a disk 170 which is rotated in one of the nodal planes. As shown in Fig. 19 this rotation is provided by a gear 185 on the disk 170, which is driven by a worm 40 through a shaft 186 rotated by a knob 187. The image of the fiducial mark appears at 161 in Fig. 17 and the image of the coincidence line appears as 171'. To operate the device the observer views the two object images and obtains coincidence by adjusting the light deviator 141. At the same time, he rotates the knob 187 until the images 161 and 171' are in coincidence, at which time the range may be read from a scale 172 against an index 173 by an auxiliary observer whose eye is shown at 174. To combine this embodiment of the invention with the invention of Case F the deviator 141 must be geared directly to the knob 187 and a zero adjustor in the form of any light deviator must be included in range finder system. Thus this Case H is equally applicable to range correction setting systems as well as to the simpler forms of autocollimators.

Having thus described various preferred embodiments of our invention, we wish to point out that it is not limited to these structures but is of the scope of the appended claims.

What we claim and desire to secure by Letters Patent of the United States is:

1. A range finder of the type having two spaced viewing points at which substantially collimated beams of light are received from the object being ranged, an optical system including at least one objective for directing the two beams into focus forming images in comparison planes, one portion of the system operating only on one of

the beams, a different portion operating only on the other beam and a ranging adjuster, said range finder being characterized by a pair of adjustment coincident elements, and means for projecting through the exact optical equivalent of the two portions, light from each of the two elements respectively, into focus in a single plane forming images of the elements coincidentally adjacent to one another, said ranging adjuster moving one of the element images relative to the other and one of the object images relative to the other by exactly the same amounts.

2. A range finder according to claim 1 in which the ranging adjuster is a light deviating means in one of said portions for deviating simultaneously the light from the object being ranged and the light from one of the elements.

3. A range finder according to claim 1 and of the coincidence type, in which said single plane and both comparison planes are all coplanar and an eyepiece is provided for viewing the object images and the element images.

4. A range finder according to claim 1 in which the elements are at least optically in the comparison planes and reflecting means are provided in each of said two portions for directing light from the elements to one side of the optical system and in which means are included for receiving this light and focusing both beams into said

single plane which is outside said optical system.

5. A range finder according to claim 1 in which said elements are a scale and an index therefor.

6. A range finder according to claim 1 in which said elements are a fiducial line and a coincidence line cooperating therewith and carried by a movable member.

10 7. A range finder according to claim 1 and of the stereo type in which said elements are at least optically in the comparison planes and reflecting means are provided in each of said two portions for directing light from the images to one side of the optical system and in which means are included for receiving this light and focusing both beams into said single plane which is outside said optical system.

15 8. A range finder according to claim 1 and of the coincidence type in which the elements are attached to lenses of equal focal length and each 20 element is in the nodal plane of its lens and in the focal plane of the other lens whereby collimated beams are formed by light from the elements through the lenses and in which reflectors are included in said portions for receiving the 25 latter beams and directing them through the portions to said single plane.

FREDERICK M. E. HOLMES.

JOSEPH MIHALYI.
